UNITED STATES PATENT OFFICE.

DICK KENDALL CASON, JR., OF NACOGDOCHES, TEXAS.

JACK FOR PUMPS AND THE LIKE.

Application filed April 10, 1924. Serial No. 705,446.

To all whom it may concern:

Be it known that I, DICK K. CASON, Jr., a citizen of the United States, residing at Nacogdoches, Texas, have invented a certain 5 new and useful Improvement in Jacks for Pumps and the like, of which the following is a specification.

My invention relates to a reciprocating jack for lifting in a straight, or approximately straight, line and is particularly adapted for pumping operations in oil and water wells, where it is desirable to raise the pump rod vertically upwards. It is also adaptable to drilling by standard methods.

15 In the ordinary type of pumping jack, the arm which engages the pump rod for reciprocating the same travels in the arc of a circle to which the pump rod is normally tangent. The result is that the rod is pulled from the vertical at both the upper and lower ends of its stroke. This leads to greater friction and wear upon the rod and also to excessive vibration in the rod whereby the crystallization of the same is hastened.

20 It is an object of the invention to provide a jack whereby the pump rod or drilling cable may be raised or lowered in an approximately vertical line without any side 25 pull.

It is another object to form a pumping installation which may be collapsed into the derrick platform out of the way when desired.

30 It is also an object of the invention to provide a jack for pumping deep wells which may place a minimum load upon the derrick platform.

Another object is to prevent vibration 35 and shock in the pump rod due to the usual jerk as the rod is stopped on the down stroke and the abrupt stop as the rod reaches the upper end of the stroke, thus producing a smooth and quiet operation;

40 It is contemplated that such a rig will be compact, light, and easily housed or moved when necessary. It will be easily installed and operated.

50 Referring to the drawings herewith wherein several embodiments of the invention are disclosed, Fig. 1 is a side elevation of a pumping jack employing my invention thereon; Fig. 2 is a top plan view thereof showing also the means for operating the jack; Fig. 3 is a side elevation of a different embodiment of my invention; Fig. 4

is a top plan view of the embodiment disclosed in Fig. 3, and Fig. 5 is a side elevation of a still different embodiment of the invention. Fig. 6 is a construction similar to that 60 shown in Fig. 4, illustrating another driving connection with the power shaft, and Fig. 7 is a construction similar to that shown in Fig. 3, but with a different driving means employed therewith.

65 In the form of my invention disclosed, in Figs. 1 and 2, I employ a construction for reciprocating a pump rod 1 working through a stuffing box in the upper end of the tubing 2 projecting through the derrick 70 floor 3, said floor being supported upon sills 4. The pump rod is reciprocated through a beam 5 performing the same function as the ordinary walking beam. Said beam is placed in an inclined position, the forward 75 end or head 6 being made up of two brackets 7, 7 secured to and projecting from the forward end of the beam. These brackets are perforated to receive a cross-pin 8 secured in a clamping member 9 upon 80 the pump rod.

The beam is secured at its lower end to a cross-head 10 slideable in a horizontal guideway 11 supported upon the supports to the platform 3. The connection between the 85 beam 5 and the cross-head or block 10, is a pivotal one and allows the beam 5 to swing relative to the cross-head.

90 The beam 5 is supported at a point 12 midway between the ends thereof upon a pivot pin forming a connection between two posts 13, 13 which are supported at their lower ends upon pins 14 secured in the sills 4 of the platform, as shown particularly in Fig. 2. It will be noted that the pins 14 are 95 directly opposite the tubing 2 and vertically beneath the head 6 of the beam. I contemplate making the length of the posts 13 approximately half the length of the beam 5, whereby the posts become the same length 100 as either the upper or lower arms of the beam 5.

105 The beam 5 is given a reciprocating motion in a horizontal direction at its lower end through a pitman 16 pivotally connected to a cross-head or block 10. The said pitman is connected at its rearward end to a wrist pin 17 upon the crank arm 18 secured upon a counter shaft 19. Said counter shaft is journaled at 20 and 21 in bearings secured 110 upon some suitable supporting base, and is rotated through a gear 22 thereon having

operative connection with a similar gear 22 upon a parallel shaft 23, also journaled for rotation in bearings supported on said base. The shaft 23 is a power shaft rotated 5 through connection with an engine shown diagrammatically at 24.

In pumping rigs such as are employed in the operation of oil wells, it is necessary at intervals to withdraw the pump rod or tubing 10 from the well, and I have shown mounted upon the uprights 25 of the derrick, a reel 26 for the cable. This reel may be operated at varying speeds through sprocket wheels 27 and 28 upon the shaft of the drum. 15 These sprockets may be rotated through connection with similar sprockets 29 and 30 upon the shaft 23, as shown in Fig. 2. The manner in which the pump 5 is reciprocated through connection with the power shaft 23, 20 will be clear from the drawing without further description.

The reciprocating of the beam 5, whereby the lower end is moved in horizontal plane, will cause the forward head 6 to move in a 25 straight vertical line directly upwardly from the well. This vertical movement will be accounted for through the fact that the beam 5 becomes the diameter of a circle whose position is constantly varying. Each 30 of the posts 13 is a radius of this circle. The point 14 will therefore always lie in the circumference of the circle, and the angle at 14 between the sill 4 and the pump rod 1 is a right angle. As the cross-head 10 moves 35 directly in the plane of the sill the head 6 must always move in a vertical line which is a projection of the vertical side of the triangle provided by the pump 1. It will therefore be seen that the head 6 will always 40 describe a straight line vertically above the well.

In Figs. 3 and 4 the installation is similar to that described in the first embodiment, the position and shape of the parts being varied somewhat. The beam 31 corresponding 45 to the beam 5 of the first embodiment has the head 6 attached to the pump rod 1, as previously described. The beam 31 is curved at 32, and the rearward ends is inclined upwardly away from the sill 4 of the derrick. Immediately above the curved portion of 50 the beam is a roller 33 mounted upon a shaft 34 in bearings 35 on the derrick platform. The roller shaft is firmly anchored to the 55 platform so as to sustain a tendency of the beam 31 to be thrown upwardly in the operation of the pump.

At the rear end of the beam 31 I provide 60 a bracket 36 extending upwardly from the beam and having a pivotal connection at 37 to a pitman 38 secured to a wrist pin 39 on a crank arm of the shaft 40 operated through the electric motor 41; between the motor 41 and shaft 40, may be used a gear reduction 65 device shown diagrammatically at 42, by

means of which the speed of the motor may be reduced. The sprocket wheels 43 and 44 upon the shaft 40 provide means for the operation of a drum 26 mounted in the derrick 25. The supporting posts 45 are pivotally 70 supported at their lower ends on pins 46 secured in the sills 4 and the upper ends of these posts are pivoted at 47 to the beam 31, as in the previous modification.

In this embodiment it will be noted that 75 the pivotal pin 46 of the post 45 need not be vertically below the head 6 of the beam, and also it is not necessary that the pivotal pin 47 be exactly midway between the ends of the beam. A vertical motion of the head 6 80 may be accomplished however in this embodiment through the differential movement given to the rear end of the beam 31 as it reciprocates. This is due to the particular 85 curve of the beam where it bears upon the under side of the roller 33. This curve is such that when the beam is reciprocated through the pitman 38 the forward end or head 6 of the beam is constrained to move in a vertical line, as in the previous modification. 90

In Fig. 6 I have shown a construction 95 practically identical with the one just described, except for the driving connection between the crank pin 39, and pitman 38 with the beam 31'. This is accomplished by providing a bracket or bearing 55 secured to the beam 31' adjacent to and on the rearward side of the pin 47. The rearward end of the beam 31 is thus unobstructed by thus having no attaching bracket thereon. The 100 operation of this construction is not materially different from the one shown in Fig. 3, but provides a somewhat more compact installation than shown in Fig. 3 embodiment. 105

In Fig. 7 the beam 31' is of the same shape as that shown in Fig. 6, and is adapted to operate in substantially the same way. It bears against the lower side of roller 33 at 110 its rearward end, and is supported on posts 45 approximately midway between the curved portion 32 and the head 6'. The head is engaged below the pins 8 upon the clamping member 9 of the pump rod 1, and operates as in the previously described construction.

The beam 31' is reciprocated in this embodiment by means of a jerk line 56 connected with a power plant at some adjacent point. It is customary in pumping operations, especially in shallow wells, to operate a plurality of pumping jacks such as are here shown, from a central power plant which is connected with the pumping jacks 115 by means of cables or rods such as is shown at 56. I contemplate attaching the line 56 to the pivotal point 47 of the jack, as shown in the drawing.

In the embodiment disclosed in Fig. 5, the 120 arrangement of the parts is not greatly dif- 125 ferent from that shown in Fig. 6, except that the beam 31 is curved at 32, and the rearward end of the beam 31 is supported on the post 45. The 130

ferent from that shown in Fig. 1. The beam 5 is supported at a point midway between its ends at 12 upon posts 13 mounted on pins 14 directly beneath the head 6' on the beam.

5 The said head 6' is shown as having the brackets 7' provided with a recess or notch on their upper sides to receive the pin 8 on the clamping member 9 of the pump rod.

The lower end of the beam 5 is pivoted 10 at 49 to the lower end of a supporting arm 50, said arm being adapted to swing upon a yoke 51 by means of a pin 52 on said arm. The yoke 51 is secured upon a cross member 53 of the derrick. The beam 5 may be reciprocated through a pitman 54 connected with a crank shaft not shown.

It will be noted that the movement of the head 6' of the beam will be approximately in a straight line, but will vary a slight 20 amount from the vertical due to the fact that the point 49 at the lower end of the beam does not move in an exactly horizontal plane. As the arm 50 upon which the beam is supported may be made of such length that its 25 lower ends describe a large arc, the variation from the horizontal will be so slight as to not materially effect the vertical movement of the head 6'.

The type of jack illustrated in the drawings has certain points of advantage over 30 the type of jack ordinarily employed for pumping or drilling purposes. It provides a vertical movement of the pump rod without the usual side movement at the upper 35 and lower ends of the stroke, and thus avoids a material amount of jar and vibration. Furthermore, in the operation of pumping or drilling devices, the pump rod or drill cable is carried down by its own weight, and 40 should be allowed to complete the downward stroke before the beam attempts to start the upward stroke. With this construction the pump rod may move downwardly to the end 45 of its stroke without material strain upon the pumping apparatus. This is due to the fact that the arrangement of the apparatus is such that the tendency of the beam is to allow the rods or tools to fall naturally, due to the connection of the supporting posts to 50 the beam, and through the particular position of the pitman 16 and crank shaft relative to the power. The rapid movement occurs when the crank shaft 18 is in a vertical position, and the movement of the post 55 13 downwardly is most rapid when the angle below the post 13 and the beam 5 is an obtuse angle. It is also to be noted that the speed of the upward stroke is slow as it approaches the upper end of the stroke, due 60 to this same construction, and the slowing down of the speed of the stroke allows the rod to stop before starting downwardly without material jerk upon the apparatus.

Another advantage is that the jack may 65 fold down into the floor of the derrick out of

the way when not in use. The two brackets constituting the head of the beam will fit around the upper end of the tubing and casting, and the device will fold together into the platform flush with the floor so as to be 70 out of the way. Another advantage is that the device may be mounted upon the platform for operation in a compact position without the necessity of a large housing for the pumping plant. The assembled device 75 with its operating mechanism is light in construction, and may be easily portable.

In the type of construction shown in Figs. 3 and 4, it is to be noted that the strain upon the platform of the derrick will be only half 80 that usually sustained. This is due to the fact that there is an upward thrust against the roller 33 approximately equal to the load of the pump rod. This is an advantage over the usual construction where the beam is pivoted in the middle and the pull downwardly upon the rearward end of the beam is equal to the load of the pump rod, thereby causing a strain upon the derrick platform equal to twice the amount of the load. 90 Furthermore, the movement of the device is largely in a horizontal direction whereby the thrust of the power stroke may be taken up easily by the sills of the derrick already 95 in place during the drilling operation.

As previously stated, this construction is especially adaptable to pumping operations, but may also be used to advantage in drilling with reciprocating rigs. It is also capable of application in other industries or 100 situations where vertical upward lift is desirable.

I do not wish therefore to be confined to the particular use for the device described in the specification further than will come 105 within the scope of the claims appended hereto.

Having thus described my invention, what I claim as new and desire to protect by Letters Patent is:

1. In a device of the character described, a platform, a beam inclined relative to said platform, a post pivotally supported at its lower end to said platform and pivotally connected at its upper end to said beam, an upwardly curved lower end on said beam, a roller above said curved end against which said lower end bears and means to reciprocate said beam.

2. In a device of the character described, an inclined beam the upper head of which is adapted to be secured to a load, a post pivotally supported on a base and pivotally connected to said beam intermediate its ends, an upwardly curved lower end on said beam, a bearing means above said curved end, and means to reciprocate said beam.

3. In a device of the character described, a platform, a beam inclined relative thereto, a post pivotally supported at its lower end 120

on said platform and connected at its upper end to said beam, a load engaging means at the upper end of said beam, the lower end being curved upwardly, a roller above said curved end, and means connected with said curved end to reciprocate said beam.

4. In a device of the character described, a platform, a beam inclined relative thereto, a post pivotally supported at its lower end on said platform and connected at its upper end to said beam, a load-engaging means at the upper end of said beam, an upwardly curved lower end on said beam, a roller secured to said platform and engaging above said curved end, and means connected with said beam to reciprocate the same.

5. In a device of the character described, an inclined walking beam pivoted on a mov-

able support, load-engaging means at its upper end, an upwardly curved lower end on said beam, and means acting as a guide for the lower end of said beam and serving to restrain the vertical movement of said lower end.

6. In a device of the character described, an inclined walking beam pivoted on a movable support, load-engaging means at its upper end, an upwardly-curved lower end on said beam, a roller above said curved lower end and acting to restrain its upward movement, the curvature of said beam allowing an approximately vertical movement of said load-engaging end, and means to reciprocate said beam.

In testimony whereof I hereunto affix my signature this 29th day of March A. D. 1924.

DICK KENDALL CASON, Jr.
